SELECTOR TUNING DEVICE

Original Filed Nov. 22, 1929

INVENTOR
JOHN O. PRESCOTT

BY *John O. Prescott*
ATTORNEY

UNITED STATES PATENT OFFICE

JOHN O. PRESCOTT, OF GLENBROOK, CONNECTICUT, ASSIGNOR TO COLUMBIA PHONOGRAPH COMPANY, INC., OF BRIDGEPORT, CONNECTICUT, A CORPORATION OF NEW YORK

SELECTOR TUNING DEVICE

Original application filed November 22, 1929, Serial No. 409,007. Divided and this application filed April 1, 1930. Serial No. 440,750.

This invention relates to automatic radio station selector means, being a division of my application Serial Number 409,007, filed November 22nd, 1929.

5 An object of the invention is to provide means whereby a station may be quickly and easily tuned in, the means visually indicating to the operator that a station is properly tuned in.

10 Another object is to provide a means as stated including means for displaying the call letters of the station as the same is tuned in.

A further object is to provide a radio dial 15 and associated means for treating the dial when a station has been tuned in on a set associated with the dial, the treatment of the dial being such that the tuning in of such station will be instantly noted when the dial 20 is again manipulated for that purpose.

Another object is to provide means for treating a radio dial whereby the proper position of the dial for tuning in various stations will be readily visible on the dial, 25 the means or method of treating the dial being such that the dial may again be treated to remove the effects of the first treatment, whereby it may be retreated for the same purpose.

30 A further object of the invention is to provide a radio dial including an opaque portion in combination with means for treating said opaque portion at desired points to form transparent or translucent lines which, when 35 properly positioned relative to any suitable indicating means, will show that a station is properly tuned in.

Additional objects and advantages will 40 become apparent from a consideration of the following detailed description taken in connection with the accompanying drawing. In this description and drawing preferred and satisfactory embodiments of the invention 45 are described and shown but it is to be understood that these are purely for the purpose of disclosing the principles of construction and operation of the invention, and that the invention is not limited to the arrangements disclosed, but that reference must be

had to the annexed claims for a definition of the limitations of the invention.

In the drawing:

Figure 1 is a view of a portion of a radio dial showing the same associated with an 55 escutcheon plate window;

Fig. 2 is a view of the escutcheon plate window of Fig. 1;

Fig. 3 is an elevational view of the means for treating the opaque surface on the dial 60 of Fig. 1, to form a translucent or transparent line thereon for the purpose of indicating when a station is tuned in; and

Fig. 4 is a plan view of the arrangement shown in Fig. 3.

In the specification and claims the word dial is used in the ordinary sense in which it is used in the radio art. That is, it indicates a circular disc, or a section of a band on the periphery of a rotatable drum, or a 70 film which may be moved in a flat plane.

Referring in detail to the drawing at 5 is shown a portion of the radio dial which may be of any preferred construction but which is shown as that of the drum type. This 75 dial may be formed of any suitable material as paper, celluloid or the like and has the usual graduated markings 6 along one edge. The dial is rotated or otherwise manipulated by any suitable means (not shown) as is 80 well known in the art, and passes in the rear of an escutcheon plate window 7 for indicating pointers 8 for co-operation with the dial 5 to show where a station is tuned in on a radio set with which the dial is associated. 85

For the purpose of the present invention, the dial 5 is preferably divided into three zones numbered respectively 9, 10 and 11. Zone 9 contains the graduations 6 while zone 11 is rendered opaque or substantially so by 90 the use of any removable opaque material applied to one surface of the said zone. If desired, the corresponding surface 12 of escutcheon plate window 7 (Fig. 2) may also be rendered opaque except for the narrow 95 slot shown. Zone 10 is provided in order that the operator may write in the station call letters at the proper points along the dial.

Figs. 3 and 4 show one form of means for 100

locating stations on the dial 5. In the operation of the device the set is tuned to bring in sharply the desired station, and the mechanism of Figs. 3 and 4 is operated to scratch a line through the opaque coating on zone 11 whereby when the dial is again manipulated and this mark or transparent or translucent line brought opposite the pointers or indicator 8 the same station will again be sharply tuned in.

For accomplishing this purpose the mechanism includes a scratching or scraping point 13 secured to or formed with a bar 14 mounted on or in stationary guides 15 whereby the bar may be moved in a straight path.

Of course, the bar 14 is mounted for reciprocatory movement in the guides 15 and means are provided for imparting such movement to the bar. As shown this means takes the form of a cam 16 mounted on a shaft 17 on which is also provided a knob or button 18 for manipulating the cam. Cam 16 has an arcuate notch 19 in which is received the end portion of a pin 20 on the bar 14.

One surface of the zone 11 being coated with an opaque removable substance it is obvious from the foregoing description and accompanying drawing that after a station has been properly tuned in, manipulation of the knob 18 to operate the cam 16 will move the bar 14 from the full line position of Fig. 4 to the dotted line position of that figure. The cam may then be manually actuated through the knob 18 to render the bar 14 to its normal position, or spring means may be provided for this purpose as shown. Such spring means comprises a pin 21 carried by the bar 14 and having one end of the coil spring 22 anchored thereto, the other end of the spring being anchored to a pin 23 carried by one of the stationary guides or brackets 15.

Movement of the scraper or scratcher point 13 across the opaque zone 11 serves to remove a portion of the opaque material, forming a line or scratch through said material to the surface of the dial 5.

This operation of tuning a station in and cataloguing it on the dial 5 by scratching a line through the opaque coating of zone 11 is repeated until all the desired stations are catalogued on the dial, each station being represented by a scratch through the opaque coating on the rear surface of the zone 11 of the dial. The call letters for the respective stations may be written on the zone 10 opposite the scratches to which they apply. Now, when it is again desired to tune in any particular station, dial 5 is manipulated to bring the line or scratch representing the selected station to a point opposite the pointers or indicators 8 of the escutcheon plate window in connection with which the dial is being used.

For the purpose of increasing the visibility 65 of the scratches or lines through the opaque

zone 11 a light 24 is placed in the rear of the dial 5, the light burning continuously during operations.

While in the foregoing description, the parts have been described in detail and with relation to particular combinations it will be apparent that changes may be made in the various combinations of parts, further it will be understood that should there be any changes in the broadcasting stations, such as 75 the assignment of new wave lengths and the like, the surface of zone 11 may again be coated with some removable opaque substance to cover up the original scratches or lines and new scratches or lines may be made to correspond with the new selections or locations of stations.

Before treatment of the zone 11 of the dial 5, the entire dial is preferably translucent or transparent and may be of any substance 80 which may be rendered more or less opaque or imperfectly translucent by a coating or treatment, the effect of which is effaceable. An example of such substances is celluloid or the like coated with a removable dark lacquer or shellac; or fibrous translucent material coated with carbon particles; or any other translucent material which may be rendered more or less opaque by fumes or other coating which does not penetrate, and may 85 be scraped or wiped off or dissolved off by any volatile or non-volatile substance.

Having thus described my invention what I claim is:

1. In combination, a radio dial including a more or less opaque portion and means to engage said portion to treat the same to make a translucent line across said portion to indicate the location of a broadcasting station on said dial.

2. In combination, a radio dial having a portion of its surface treated to render it more or less opaque, and means adapted to be moved across said treated surface to form a translucent line thereacross to show the location on the dial of a particular broadcasting station.

3. In combination, a radio dial having a portion of its surface coated to render it more or less opaque, means adapted to be moved across said surface to scratch through said coating whereby a translucent line is formed through said portion to indicate the location on the dial of a radio broadcasting station.

4. The combination as in claim 3, said means including a reciprocating means carrying the scratcher means.

5. The combination as in claim 3, said means including reciprocating means and cam means to operate the reciprocating means.

6. The combination as in claim 3, said means including reciprocating means, cam means to operate the reciprocating means in 130

one direction, and spring means to operate it in the opposite direction.

7. In combination, a radio dial, a source of light in the rear of said dial, a portion of said dial being more or less opaque, an indicator means, and means to treat said opaque portion of the dial to make translucent lines thereon to indicate the location thereon of broadcasting stations, whereby when said translucent lines are opposite said indicator means the light will be visible through them and a station will be properly tuned in.

Signed at New York, county and State of New York this 17th day of March, 1930 A. D.

JOHN O. PRESCOTT.
